UNITED STATES PATENT OFFICE.

CHARLES A. HOTCHKISS, OF BRIDGEPORT, CONNECTICUT, ASSIGNOR TO
IVES, BLAKESLEE & CO., OF SAME PLACE.

TOY.

SPECIFICATION forming part of Letters Patent No. 339,101, dated March 30, 1886.

Application filed January 14, 1886. Serial No. 188,526. (No model.)

To all whom it may concern:

Be it known that I, CHARLES A. HOTCHKISS, of Bridgeport, in the county of Fairfield and State of Connecticut, have invented a certain 5 new and useful Improvement in Toys, of which the following is a specification.

This improvement relates to toy dancers.

I will describe in detail a toy dancer embodying my improvement, and then point out 10 the novel features in the claims.

In the accompanying drawings, Figure 1 is a front view of a toy dancer embodying the improvement, part of the outer covering or dress being removed. Fig. 2 is a side view of 15 the same, the outer covering or dress being partly removed. Fig. 3 is a side view of a toy of modified form embodying the improvement, the outer covering or dress being broken away.

20 Similar letters of reference designate corresponding parts in all the figures.

In Figs. 1 and 2, A designates a train of wheel-work, which may be of any suitable kind. It is operated by a spring, a. It is 25 made of such dimensions that it will fit in a case, B, forming the body of the dancer. This case may advantageously be made of sheet metal. The head of the dancer may be made of cast metal. It is fastened in an appropriate 30 manner to the case B. The train of wheel-work comprises a shaft, a', which has a crank, a', on the front end. Hung on the crank a' is a rod, a³, which at the lower end has a bifurcated portion, a⁴. The ends of this bifurcated 35 portion bend backward as they extend downward to a point about midway between the front and back of the train of wheel-work. They have the thigh-sections C of the dancer's 40 legs attached to their lower ends by flexible connections. At the lower ends of these thigh-sections the calf-sections d are attached by flexible connections. Feet C² are connected flexibly to the bottom of the calf-sections. As the wrist of the crank a' revolves it raises 45 and lowers the legs and swings them sidewise. The head of the dancer is shown as having a movable jaw, consisting of a lever, D, fulcrumed upon a pin, d, and having its rear portion connected to the rod a³. The crank a'

therefore also vibrates the jaw. The connection of the rod a³ with the jaw-lever D is advantageous, because it prevents the rod, and consequently the bifurcated portion a⁴, from having an excessive motion sidewise imparted to them by the revolution of the crank. Preferably the train of wheel-work will comprise 55 a fly-wheel, a⁵, for carrying the crank over dead-centers.

Any desired style of human being may be represented by the dancers. Many other living creatures may be depicted, if desirable. The dancer may have any preferred style of outer covering or dress, E. A cord, G, fastened to the head of the dancer, affords provision for suspending the dancer with the feet 65 in close proximity to a table or like article. The movements of dancing will then be simulated. If the dancer be suspended in air or laid down on a support, it will have a very grotesque aspect.

The toy shown in Fig. 3 is like the one shown in the other figures, except that it has two separate cranks, a², and two rods, a³, suspended therefrom. It has, also, another crank, a⁶, which is connected by a rod, a⁷, to the jaw-lever D.

70 What is claimed, and desired to be secured by Letters Patent, is—

1. A pendulous figure having, in combination, a train of wheel-work operated by a prime mover, a crank operated by said wheel-work, a rod connected to said crank, and legs hanging from the rod and deriving an up-and-down motion therefrom, said legs having no other support from the body, substantially as specified.

2. A pendulous figure having, in combination, a train of wheel-work operated by a prime mover, a crank operated by said wheel-work, a rod connected to said crank, a jaw-lever 85 connected to said rod, and legs hanging from the rod, both the jaw and legs deriving motion from said rod, substantially as specified.

CHARLES A. HOTCHKISS.
